UNITED STATES PATENT OFFICE.

TOLBERT LANSTON, OF WASHINGTON, DISTRICT OF COLUMBIA, ASSIGNOR,
BY DIRECT AND MESNE ASSIGNMENTS, TO THE LANSTON TYPE MACHINE
COMPANY, OF SAME PLACE.

FORM OF TYPE.

SPECIFICATION forming part of Letters Patent No. 364,524, dated June 7, 1887.

Original application filed September 30, 1885. Serial No. 178,671. Divided and this application filed July 3, 1886. Serial No. 207,159.
(No model.)

To all whom it may concern:

Be it known that I, TOLBERT LANSTON, of Washington, in the District of Columbia, have invented certain new and useful Improvements 5 in the Art of Forming Justified Lines of Types; and I do hereby declare the following to be a full, clear, and exact description of the same, reference being had to the accompanying drawings, forming part of this specification, 10 and to the figures and letters of reference marked thereon.

It is well known that in ordinary composition, where common type is used, it rarely ever happens that a series of words regularly 15 and uniformly spaced exactly fill a line of given length, the rule being that a space of greater or less length is left at the end of each line which must be filled up or absorbed by the usual process of justification—that is to 20 say, by the introduction between the words or the several letters composing the words in the line of composition of additional spaces, or by the substitution of wide for narrow spaces, or vice versa. In the practical working of this 25 system, after each line is set up, the types composing it are required to be shifted and separated for the introduction and distribution of the justifying space types or quads employed, and the justification when accomplished usually 30 leaves the spacing of the lines irregular, being dependent entirely upon the skill of the compositor.

The object of my invention is to produce lines of justified type—that is to say, lines 35 composed of type which, when assembled, will exactly fill the line and require no shifting, justification, or manipulation whatever. This object I attain by distributing the space required to be absorbed by justification among 40 the type in the process of formation.

I will now proceed to describe several ways of carrying my invention into practice.

Referring to the accompanying drawings, Figure 1 is a fac-simile of an impression taken 45 from type of standard dimensions, and of a style known as "double English," this variety of type being selected because of its large size and the resulting convenience in graphically representing the hereinafter-described modes

of carrying out the invention. Fig. 2 is a 50 diagrammatic view representing an unjustified line comprising the characters shown in Fig. 1, the types being shown in outline and on a scale of 2 to 1. Fig. 3 is a diagrammatic view representing the same characters illustrated in 55 Figs. 1 and 2 justified according to what I term "the percentage-of-variation system." Fig. 4 is a similar view illustrating the line justified according to what I term "the system of uniform variation." Fig. 5 is a similar 50 view illustrating a modification of the system shown in Fig. 4, the variation being apportioned among the space types or quads only. Fig. 6 is a view of a portion of a form of type composed of lines produced in accordance with 65 my invention.

Similar letters and numbers in the several figures indicate corresponding parts.

As the space between *b* and *c* represents a certain percentage of the space between *a* and *b*, it follows that if to each division of the space *a b* there be added a corresponding percentage of its width the result will be the filling out 70 of the line. It is also true that the distance from *b* to *c* bears a fixed relation to the number of divisions of the line *a b*; hence if to 75 each division is added its proportional part of the space *b c* the result will be, as before, the filling out of the line.

An illustration of the application of my invention by what I term "the percentage-of-variation system" is represented diagrammatically in Fig. 3.

The space *b c*, Fig. 2, to be filled by justification is approximately ten per cent. of the space 85 *a b*; hence if there be added to each subdivision of the space represented by the line *a b*—or, in other words, to each of the twenty-three normal types which we have found would be contained in said space ten per cent. of its 90 width—the line will be filled out or justified.

In producing types which will, when associated together, exactly fill out the line *a c*, it is therefore only necessary that they be constructed of a width ten per cent. above the normal. 95 This process has been followed in the making of Fig. 3, the types there being represented, as nearly as practicable, as increased

in width ten per cent. above the types shown in Fig. 2.

An illustration of the application of my invention by what I term "the system of uniform variation" is represented diagrammatically in Fig. 4. In this system, instead of forming the type comprising the line of a width increased above the normal on the percentage plan, the space to be filled by justification is distributed uniformly among them—that is to say, each of the types for the line is made of a width increased above the normal an amount equal to the space to be filled by justification divided by the number of type which would compose the unjustified line. Thus, as represented in Fig. 4, each type is shown of a size increased above the normal types shown in Fig. 3 one twenty-third of the space between *b c*, the result being that when assembled they fully occupy the line *a c*.

As is obvious, instead of distributing the increase among all the types, whether by the system of uniform variation or the percentage of increase system in the line, it may be apportioned among certain of them only—as, for example, among the space type or quads. An example of this is shown in Fig. 5, in which the space-types 2, 4, 6, 8, 13, 16, and 21 are each made of a width increased above the normal, as indicated in Fig. 2, one-seventh of the space *b c* to be filled by justification, the other types in the line being made of normal size.

In carrying out my invention by whichever of the systems indicated it should be understood that the types for each line of composition are formed with special reference to the needs of that line alone, and the several lines are associated together in forms, so that impressions may be taken from them, either for direct print-

ing or for forming matrices for stereotype or 40 electrotype purposes.

The variations in the width of the types referred to herein relate solely to variations in the bodies and not to the impression-faces thereof, which remain normal, and in this connection it may be stated that in the production of lines of ordinary size type the variations are so slight as to be imperceptible to the eye, while uniformity of spacing is attained in greater perfection that can be secured in ordinary 50 hand-composition, where justification is effected by the employment of spaces or quads varying in width and unequally distributed.

The various systems by which my improved lines and forms are produced form the subject-matter of other applications filed contemporaneously herewith and numbered, respectively, 207,156, 207,157, 207,158, and a machine competent for carrying into effect those systems forms the subject of still another application, filed September 30, 1885, No. 178,671, of which this is a division.

Having thus described my invention, what I claim as new is—

A form from which to print or stereotype, 65 composed of a series of lines of matter, each consisting of a succession of separate types the bodies of a predetermined number of which are varied as to width from the normal and from types representing the same characters or 70 spaces in other lines in the form, thereby rendering each line self-justifying, substantially as described.

TOLBERT LANSTON.
